PRESSER-BAR MECHANISM FOR SEWING MACHINES

Frederick F. Zeier, Stratfield, Conn., assignor to
The Singer Manufacturing Company, Elizabeth, N. J., a corporation of New Jersey

Application November 19, 1945, Serial No. 629,363

23 Claims. (Cl. 112—237)

1

This invention relates to sewing machines and, more particularly, to means for raising a presser-bar and/or an upper four-motion feeding mechanism off the sewing machine work-support.

The usual sewing machine is equipped with some type of a work-presser mechanism which is urged toward the work by means of a spring. Working in cooperation with the work-presser or presser-foot mechanism for the purpose of feeding the work past the stitching mechanism is the usual lower four-motion feed-dog. This feed-dog commonly traverses an elliptical path which has its major axis substantially parallel to the sewing machine throat-plate. The feed-dog is positioned relative to the throat-plate so that, when the feed-dog is traversing the upper portion of its path, the feed-dog teeth will project above the top surface of the throat-plate. Therefore, during the first half of the feeding movements of the feed-dog, when the dog is above the top surface of the throat-plate, the feed-dog will move both upwardly and in the direction of feed, thereby to grip the work against the presser-foot and actually lift the presser-foot and presser-bar a short distance. During the latter half of the feeding movement, the feed-dog moves both downwardly and in the direction of feed before dropping below the top surface of the throat-plate. The downwardly spring-biased presser-foot and the presser-bar drop with the feed-dog until the down-movement of the work is arrested by the throat-plate. The work then remains stationary while the feed-dog returns below the level of the upper face of the throat-plate to its initial position to begin another feeding stroke. These engagements of the feed-dog with the work usually occur once for each stitch made by the machine, and the presser-bar and foot must rise and fall with the feed-dog once for each stitch.

Due to the movement of the feed-dog in the direction of feed, the work is drawn under the sole portion of the presser-foot, thereby introducing a sidewise thrust which sets up frictional forces between the presser-bar and its bearings and thus this frictional force, coupled with the natural inertia of the usual presser-bar, tends to prevent the presser-bar from returning quickly to its lower position when the feed-dog moves downwardly.

As the speed of a sewing machine is advanced, it becomes increasingly difficult to return the presser-foot quickly and forcibly down upon the work at the end of the feed-advance stroke of the feed-dog. At these higher speeds of oper-

2

ation of the machine, the friction between the presser-bar and its bearings is increased due to the increased speed of the work under the presser-foot sole portion, and this friction, coupled with the inertia of the machine parts builds up to the extent that the spring which is used to return or lower the presser-bar cannot function to lower completely the presser-foot between consecutive work-disengaging and work-engaging movements of the feed-dog.

Sewing machines having an upper four-motion feeding mechanism of the character known as the alternating presser type also present substantially the same problem as that hereinabove discussed. In this type of mechanism, there is employed an automatic presser and feeding-foot lifting mechanism which is normally dependent upon the resistance imposed by the work or its support to the downward movement of either the presser-foot or feeding foot, in order to provide a fulcrum for lifting the other of said members. Therefore, if any inertia or cramping of the parts occasions a sufficient resistance before either of said members in its descending movement reaches the work, the necessary fulcrum will be untimely provided and neither of said members will engage the work with the requisite pressure to insure a proper work-feeding action. The liability of imperfect operation of feeding mechanisms of this character increases with the speed of operation of the machine, due in a large measure to inertia of the parts and also because the spring which depresses the presser and feeding foot elements cannot recover with sufficient rapidity to overcome the upward movements thereof. At extreme high speeds, a degree of inefficiency may be reached wherein neither the presser-foot nor the feeding-foot perceptibly engages the work.

One method of overcoming the above discussed difficulties is to provide the mechanism, whether it be of the usual simple presser-bar or of the upper four-motion feeding type, with a spring capable of exerting a force materially greater than that heretofore used. Although the addition of this spring helps to obviate the one difficulty, it was found that the necessary force of the spring required excessive manual effort to lift the presser-foot off the work. Even if the machine operator could exert the requisite amount of force to lift the presser-bar, she would soon tire of such arduous work. It has been found that an operator can, with comfort, continue to operate a presser-bar lifting device if the maximum force required does not exceed

ten pounds. However, many of the present type sewing machines require a spring force of about fifty pounds in order to urge the presser-foot against the work with the requisite force to properly feed the work at all different speeds of operation of the machine.

It is, therefore, an object of this invention to provide a sewing machine with presser-bar lifting means which will require a minimum of force to operate.

Another object of this invention is to provide an improved means for applying to and removing spring pressure from a work-presser mechanism.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

Fig. 1 represents a rear side elevation of a sewing machine in which the present invention is incorporated.

Fig. 2 represents a top plan view, partly in section, of the present machine.

Fig. 3 represents a left side elevation of the sewing machine, showing the stitching and feeding mechanisms with the bed and work-supporting plate in section, and with the needle in its uppermost position.

Fig. 4 represents a left side elevation of the stitching and feeding mechanisms as removed from the sewing machine frame and with the needle in its lowermost position.

Fig. 5 is a detail view, in elevation, of the feed-lift crank in its raised or inoperative position, with the lock-pin device sustaining the crank in this position.

Fig. 6 represents a sectional view of the upper feeding and stitching mechanism taken substantially along line 6—6 of Fig. 1.

Fig. 7 represents a sectional view of a portion of the feed- and presser-bar actuating mechanisms taken substantially along line 7—7 of Fig. 3.

Fig. 8 represents a sectional view showing a portion of the presser-bar with its associated elements and taken substantially along line 8—8 of Fig. 6.

Fig. 9 represents a sectional view showing a feed-bar lifting means and taken substantially along line 9—9 of Fig. 6.

Fig. 10 represents a sectional view showing the presser-lifting mechanism in its normal position and taken substantially along line 10—10 of Fig. 2.

Fig. 11 represents a detailed view of that Geneva stop mechanism which actuates the spring-disengaging toggle mechanism.

Fig. 12 is an illustration in side elevation of the presser-lifting mechanism at that point in its cycle at which the presser spring is fully relaxed.

Fig. 13 represents an enlarged detailed view in side elevation of the fulcrum member and the presser-bar lifting arm which is engaged thereby.

Fig. 14 is an illustration of the presser-lifting mechanism at that point in its cycle at which the presser-bar and top feed-bar are fully raised off the work.

Fig. 15 represents a detailed view of a portion of the presser-lifting mechanism taken substantially along line 15—15 of Fig. 1 and showing the

mechanism at that point in its cycle corresponding to that illustrated in Fig. 12.

Referring to the drawings, the invention is embodied in a sewing machine having a frame comprising a bed 16 from one end of which rises a standard 17 of an overhanging bracket-arm 18 terminating in a head 19. Journaled for rotation within this frame is a main-or arm-shaft 20 carrying at its outer end the usual belt-driven balance-wheel 21 and at its inner end a counterbalanced needle-bar actuating crank 22. Shaft 20 is connected by a clip-belt 23, herein shown incompletely, to a belt-pulley 24 fast upon the outer end of a lower main- or bed-shaft 25 journaled for rotation in the bed 16, the ratio between the shafts 20 and 25 being one-to-one.

Actuated by the bed-shaft 25 is the usual lower four-motion work-feeding mechanism, including a feed-dog 26, and the looper mechanism including a chain-stitch looper 27. For the sake of brevity, a detailed description of the four-motion feeding mechanism will not be given herein, inasmuch as the same is fully described and claimed in my U. S. Patent No. 2,292,258, Aug. 4, 1942.

With regard to the looper mechanism disclosed in the drawings, it will suffice to say that the looper 27 is preferably of the two motion type having loop-seizing and shedding movements only in the line of feed, the looper advancing to seize the needle-loop in a direction opposed to the direction of feed.

Referring now to the mechanism within the machine-head 19, it will be seen in Figs. 1, 3 and 4 that a needle-bar actuating link 28 is pivotally mounted upon the crank 22 by means of a screw 29. The lower end of the link 28 is apertured to receive a pin 30 integral with a split collar 31 clamped upon the usual needle-bar 32. Carried at the lower end of the needle-bar 32 is a suitable needle 33. Through the mechanism just described the needle-bar 32 is reciprocated endwise in proper timed relation with the complementary looper 27 to produce chain-stitches.

The needle-bar 32 is journaled in bearing members 34 and 35 projecting from the needle-bar frame 36 which is provided with a horizontally projecting fulcrum-rod 37 journaled within the lug 38 of the machine head 19.

The needle-bar-frame 36, in the machine illustrated, is oscillated in timed relation with the four-motion feed-dog 26 through mechanism comprising a rock-lever 39 (see Fig. 1) preferably clamped at its lower end 40 upon the end portion of the fulcrum-rod 37. At its upper end, the rock-lever 39 is pivotally connected, by means of a bolt 41 and nut 42 to one end of a relatively short pitman 43 formed at its other end with a strap 44 embracing an adjustable eccentric 45 secured to rotate with the arm-shaft 20. It will be understood that as the arm-shaft 20 is rotated, the eccentric 45 actuates the pitman 43 which in turn operates the rock-lever 39 to oscillate the needle-bar-frame 36 about the axis of the fulcrum-rod 37. The amplitude of oscillatory movement imparted to the needle-bar-frame is dependent upon the amount of eccentricity of the eccentric 45 and, in order to vary the amplitude of the oscillatory movements of the needle-bar frame to harmonize with the stitch-length to which the lower feeding mechanism is set, the eccentric is made adjustable. A complete description of this type of adjustable eccentric may be found in the U. S. patent of W. Myers, No. 2,128,031, Aug. 23, 1938. For a more detailed description of the present type of needle-

bar mechanism, reference may be had to my U. S. Patent No. 2,329,681, Sept. 14, 1943.

Referring particularly to Figs. 3 and 4, the needle-bar frame 36 has a vertically apertured bearing lug 46 formed thereon adjacent the bearing portion 35. Slidably mounted within this bearing lug 46 is a top feed-bar 47 carrying at its lower end a feeding foot 48 which is adapted to cooperate with the needle 33 and the lower feed-dog 26 in the feeding of the work over the bed-plate 49. Since the feed-bar 47 is carried by the needle-bar frame 36, the latter element will impart the same amplitude of vibrating motion in the line of feed to both the needle-bar 32 and the top feed-bar 47.

The upper end of the top feed-bar 47 is provided with a cross-pin 50 which is slidably received within the forked free end 51 of a substantially horizontally disposed feed-lift lever 52. The confined end of the lever 52 is pivotally mounted upon a fulcrum-pin 53 which is secured within the lower rear portion of the machine head 19.

In order to prevent the feed-bar 47 from turning about its longitudinal axis, the top portion thereof is provided with a pair of cheeks 54 which carry the cross-pin 50 and which embrace the forked portion 51 of the lever 52.

The machine head 19 is provided with a vertically disposed stationary bearing member 55 in which a presser-bar 56 is slidably mounted so as to be located slightly rearwardly of the top feed-bar 47 and out of the line of feed at that side of the line of feed nearest to the machine bracket-arm 18. A usual type of presser-foot 57 is carried by the lower end of this presser-bar 56. Formed in the upper portion and between the ends of the presser-bar 56 is a slot 58, Fig. 8, adapted to receive the free end of one arm 59 of a bell-crank lever which is pivotally carried by and at the center of percussion of the feed-lift lever 52.

This bell-crank lever comprises the above noted arm 59 carried by one end of the pivot pin 60, to the other end of which is secured, by means of a screw 61, a second arm 62 which is pivotally connected by a pin 63 to the lower end of a link 64. The pin 60 passes through the apertured bearing portion 65 of the lever 52 whose center of percussion lies along the axis of bearing portion 65.

The upper end portion of the link 64 is connected by means of a pin 66 to an actuating crank 67 carried by one end of a rock-shaft 68 which is journaled in bearing lugs 69 and 70 provided on the machine bracket-arm 18 and head 19, respectively. The rock-shaft 68 is disposed in parallelism with the needle-bar actuating shaft 20.

Secured upon the opposite end portion of the rock-shaft 68, by means of screws 71, is a short crank 72 carrying a pin 73 which is pivotally embraced by the forked end of a pitman 74 whose other end terminates in an eccentric strap 75. Strap 75 embraces an adjustable eccentric 76 secured to rotate with the arm-shaft 20. It will be understood that as the arm-shaft 20 is rotated, the eccentric 76 actuates the pitman 74 which, in turn, imparts rocking movements to the rock-shaft 68 through the medium of the crank 72. The amplitude of these movements may be varied by adjusting the throw of the adjustable eccentric 76. For a more complete description of an adjustable eccentric of this type, reference

may be had to the U. S. patent of A. H. De Voe, Reissue No. 14,218, Nov. 28, 1916.

Pressing downwardly upon the feed-lift lever 52, at a point between the bell-crank pivot point and the forked end 51 thereof, is one end of a spring-biased blade-lever 77 which is located outside of and rearwardly adjacent to the machine bracket-arm 18. The other end of this lever 77 is biased upwardly by means of a coil spring 78 which is operatively connected to an arm 79 mounted upon the bracket-arm 18. The lower end of the spring 78 is pivotally connected to the lever 77 by means of a bolt 80 and nut 81. As illustrated more particularly in Figs. 6, 9 and 10, lever 77 is fulcrumed adjacent to the feed-lift crank 52 upon a knife-edge 82 of a fulcrum-piece 83 extending from a stub-shaft 84 which is rockably mounted within an aperture 85 (Fig. 6) formed in the lower portion of the machine head 19. In order to prevent the spring-biased lever 77 from exerting any side thrust upon the feed-lift lever 52, a steel ball 86 is held, by means of a sheet metal cage 87, between said lever 77 and crank 52 by means of screws 88.

Referring particularly to Figs. 6 and 9, the lever 77 is apertured so as to afford clearance for a guide-pin 89 projecting upwardly from the shelf portion 90 of the head 19 and extending through the forked end of a guide-arm 91 which is clamped by means of a screw 92 to the upper reduced portion of the presser-bar 56. Thus the presser-bar 56 is prevented from turning about its longitudinal axis and at the same time the pin 89 prevents the lever 77 from moving sidewise.

The oscillatory motions of the above noted rock-shaft 68 cause the bell-crank lever 59, 62 to swing in a vertical plane about its pivot pin 60 in the feed-lift lever 52, so that the arm 59 thereof successively tends to lift and depress the presser-bar 56. When the presser-bar 56 is depressed, however, its presser-foot 57 engages the throat-plate 93, or the work carried thereby, and further movement of the bell-crank lever can only result in raising the pivot point thereof, which latter action will, of course, raise the forked end 51 of the feed-lift lever 52 with the consequence that the top feeding-foot 48 is lifted clear of the throat-plate 93, as is illustrated in Fig. 3. Continuous oscillation of the rock-shaft 68 will, therefore, cause the presser-bar 56 and the top feed-bar 47 alternately to rise and fall, and the spring-biased lever 77 being in continuous engagement with the feed-lift lever 52, it will have its force transmitted to either the presser-bar or to the top feed-bar, depending upon which one of the two elements is in engagement with the throat-plate or work. The motions of the rock-shaft 68 are synchronized with those of the needle-bar 32 so that the usual compound feeding motions will be effected.

Adjustment of the rock-shaft actuating eccentric 76 will effect adjustment in the amplitudes of the relative vertical movements imparted to the presser-bar and top feed-bar.

As hereinabove noted, one end of the lever 77 is pivotally secured to the coil spring 78 by means of the bolt 80. Referring more specifically to Figs. 1, 2, and 10, the lower end of the spring 78 is secured to the lower cup-shaped member 94 which is telescopically fitted within the upper and reversely directed cup-shaped member 95 whose upper portion has a threaded rod 96 projecting upwardly therefrom. Clamped upon the rod 96 is a split collar 97 having a threaded bolt portion 98 extending laterally therefrom. Pivotally em-

bracing the bolt 98 is the arm 79 held upon the bolt by means of nuts 99. The upper end of the spring is suitably secured to the member 95, thus to bias the lever 77 upwardly. The two cup-shaped members 94 and 95 form a substantially airtight unit whose purpose is to dampen the violent spring vibrations which would otherwise occur when the spring 78 passes through its critical phases. A rubber spacer 100 is disposed within the spring to limit lateral vibrations thereof.

The applied pressure of the spring 78 may be varied by shifting the rod 96 relative to the clamp collar 97, when loosened, by means of a stop-nut 101 which is carried by the threaded upper portion of the rod 96. The clamping screw 102 is used for tightening the collar 97 about the rod 96 in the set position of the collar.

Referring particularly to Fig. 10, the fulcrum point 82 of the spring-biased lever 77 is so located that the lever is of the first class; the portion thereof extending forwardly of the fulcrum point 82 being very much shorter in length than that portion which extends from the lever pivot point at 80 to the fulcrum point at 82. By means of the lever, or multiplying means 77, the amplitude of vertical movement of the feed-lift lever 52 is, in a preferred form of the device, multiplied by five at the effective end of the lever 77, thus to impart to the lever a force five times greater than the spring would impart thereto if it were acting directly upon the lever. Thus, a relatively light spring is adequate for supplying the proper pressure to the presser-foot and top feeding foot. Tests have proven that by using such a multiplier, superior results have been attained as compared to the results attained when using the same top feeding and presser elements but with a spring having about five times the stiffness of spring 77 and applied to bear directly upon the lever 52. Apparently there is much advantage to be gained by using a light weight spring coupled with a "multiplier" as compared to using a heavier weight spring which is applied directly upon the lever 52. These tests have shown that the use of the present multiplier mechanism completely obviates the tendency of the feet 48 and 57 to flutter when the machine is operating at a high rate of speed. It is an advantage to use a spring having a high natural frequency for this purpose.

From the above description it is to be understood that through the medium of the lever 77, the spring 78 exerts a tremendous force upon the lever 52. To raise the feet 48 and 57 against this force would require a rather awkward and impractical mechanism, or one that would require the application of a manually exerted great force. The present invention is applied to the above described machine for the purpose of providing a manually operable presser- and top feed-bar lifting means designed to keep at a minimum the lifting force required. Broadly, these means comprise elements adapted, under treadle-controlled action, to render the coil spring 78 ineffective and to relatively shift the knife-edge fulcrum 82 and the spring-biased lever 77 to permit the presser- and feed-bars freely to be raised off the work.

Specifically, the present lifting mechanism comprises a self-contained frame member 103 secured to the standard 17 by means of the screws 104 which are threaded directly into the standard. Projecting inwardly from two sides of the member 103 is an edge portion 105 (Fig. 2), which functions partially to enclose the mech-

anism contained within the unit. Upon this frame are mounted two sets of Geneva stops geared together in order to provide a series of successive motions all produced by a single downward movement of the usual foot-actuated treadle (not herein shown) which is connected to the Geneva stops by means of a chain 106 and a pivoted arm or manually operable member 107, to which the chain is secured by means of a stud 108. The arm 107 is pivotally carried upon a shaft 109 entering an aperture 110 provided in the frame 103. The free end portion of the arm 107 has a lip portion 111 upon the end of which is carried, by means of screws 112, a segment-gear 113. This segment-gear 113 meshes with a gear 114 mounted upon a rockable stub-shaft 115 and secured by means of screws 116 to a Geneva driving element 117 which in turn is secured upon the shaft 115 by means of a set screw 118.

Carried by one end portion of the element 117 is a pin 119 adapted to slidably enter a slot 120 of a Geneva driven element 121 which is mounted, by means of a set screw 122, upon a rockable shaft 123 journaled in a portion 124 of the frame 103 (see Fig. 15). Mounted upon that end of the shaft 123 remote from the element 117 is a crank 125 carrying at its outer end portion a pin 126 upon which is pivotally mounted the lower end of a substantially upright link 127. The upper end portion of the link 127 carries a pin 128 which connects the link to a toggle joint comprising the double arms 129 and 130. Arms 130 are pivotally mounted upon a stud 131 carried by the frame 103 and arms 129 are pivotally connected, by means of a pin 132, to arm 133 which is pivotally mounted upon a shoulder stud 134 carried by the frame 103. The hereinabove noted arm 79 is integral with arm 133 and therewith forms a bell-crank lever which is connected to the spring-carrying rod 96.

From the above description, it is to be understood that, responsive to an initial downward movement of the treadle-chain 106, the segment gear 113 will turn gear 114, thereby carrying the pin 119 upwardly to effect an upward movement of the slotted portion of the element 121. As the driven element 121 turns about its axis, it rocks the shaft 123 which, in turn, will rock the crank 125 upwardly and elevate the link 127. This upward movement of the link 127 will flex the toggle joint, thus to swing the arm 79 of the bell-crank lever downwardly to the extent that the spring 78 will be completely relaxed. This completely removes downward force upon the feet 48 and 57. By using a force-multiplying means such as the present toggle joint for rendering the spring 78 ineffective, little force is required to be exerted upon the link 127.

Fig. 10 illustrates the present lifting mechanism in its normal condition, with the toggle arms 129 and 130 in their straightened position and with the spring 78 fully distended, to the end that it exerts its pressure upon the ball 86. Fig. 12 illustrates this mechanism when the toggle is broken and the spring is completely relaxed.

Pivotedly mounted upon the stud 134 and adjustably secured to arm 79, by means of a set screw 135, is an arm 136 having a cam portion 137 thereon which is adapted to engage a plunger 138 for the purpose of releasing the tension between the disks 139 of a usual type of needle-thread tension unit. The cam is adapted to

engage the plunger only when the arm 136 swings to the position shown in Fig. 12.

Although the initial downward movements of the chain 106 and arm 107 were effective to relax the spring 78, it will be seen from Fig. 12 that there is very little clearance between the lever 77 and the fulcrum point 82, and as a consequence the fulcrum point 82 must be removed before the presser-bar 56 can be raised any appreciable distance above the throat-plate. Therefore, mechanism has been provided in the present device for the purpose of swinging this fulcrum point out of the path of lever movement.

Referring to Fig. 12, it will be seen that further movement of the treadle chain will not move the bell-crank and coil spring 78, as the pin 119 will merely swing clear of the slot 120 and the circular portion 140 of the driver 117 will engage the corresponding circular hollow 141 provided in the driven element 121 and thus lock the element 121 in the position shown.

Referring to Figs. 1, 10, 15 and 11, the gear 114 meshes with a second gear 142 which is mounted upon one end of a stub-shaft 143 by means of a screw 144. The stub-shaft 143 carries at its other end a Geneva driving element 145 carrying a pin 146 which is adapted to enter a slot 147 of a Geneva driven element 148 which is pivotally mounted upon a stud 149 carried by the frame 103. Provided upon the driven element 148 is a segment gear portion 150 in mesh with a rack portion 151 provided on a rock-bar 152 which is slidably mounted within an apertured lug 153 provided on the frame 103 and the aperture 154 formed in the head 19.

The forward end portion of this rock-bar 152 is also provided with teeth 155 adapted to mesh with gear teeth 156 provided on the end portion of the above noted stub-shaft 84 which carries the knife-edge 82 and, therefore, any forward linear movement that may be imparted to the rock-bar will be effective to rotate the stub-shaft 84, thereby to remove the fulcrum point from the spring-biased lever 77 for the purpose of providing proper clearance between the lever 77 and the fulcrum so the lever 52 may be freely raised.

Threaded into the fulcrum-piece 83 of the stub-shaft 84, at a point eccentric to the axis of rotation thereof, is a screw 157 of which an exposed shoulder portion 158 (see Figs. 6, 9 and 13) enters a slot 159 provided adjacent one end portion of a sheet metal arm 160, the other end of which is pivotally secured to the under body of the machine bracket-arm 18 by means of a screw 161. The free end of the arm 160, adjacent the slotted portion thereof, is bent to form a lip 162 and underlies the guide-arm 91 carried by the presser-bar 56. A turning motion of the stub-shaft 84, therefore, throws the screw 157 in an arcuate path, thereby raising the free end portion of the sheet metal arm 160 which, in turn, lifts the presser-bar 56. This upward movement of the presser-bar lifts the top feed-bar 47 also, through the medium of the bell-crank lever 59, 62 which is pivotally carried by the feed-lift lever 52.

Referring to Fig. 13, it is to be understood that the slot 159 is arcuate in shape and disposed at an angle such that an initial turning movement of the stub-shaft 84, in the direction indicated, will be effective to drop the arm 160 slightly, thus to introduce a slight time delay before the arm is lifted, to the end that the fulcrum point 82 will

be removed from the lever 77 before the bar 56 is raised.

Referring now to Fig. 10, which illustrates the lifting mechanism in its normal position, the driving element 145 is provided with a circular portion 163 which engages the circular hollow 164 of the driven element 148 for the purpose of locking the latter element in its initial position.

The cycle of the first Geneva stop mechanism, 10 which is adapted to relax the spring 78, has been heretofore described, and from an inspection of Figs. 10, 12 and 14, it will be seen that this first Geneva stop is synchronized with the second Geneva stop which is adapted to shift the fulcrum 15 and lift the presser mechanism. Fig. 12 illustrates the lifting mechanism at that point in its cycle where the first Geneva stop has completely relaxed the spring 78 but the driver 145 of the second Geneva stop at this point has rotated from its initial position (shown in Fig. 10) to a position 20 where its pin 146 is about to enter the slot 147 of driven element 148, thus to initiate movement in this latter element. It is to be understood, therefore, that no movement can be imparted to the element 148 until the spring 78 is relaxed completely.

Referring to Fig. 12, the spring is relaxed and, therefore, further movement of the chain 106 will be effective to urge the pin 146 into slot 147 for the purpose of driving the element 148 in a clockwise direction, to the end that its teeth 150 will urge the rock-bar forwardly and actuate the stub-shaft 84 as above described. During this portion of the cycle, it will be noted that pin 119 works 30 clear of the slot 120 and thus the element will continue to turn without rotating the element 121.

From the above description, it will be understood that a single downward movement of the chain 106 will produce three successive actions 40 within the lifting mechanism. The spring 78 is first relaxed by the action of the first Geneva stop, the second Geneva then is activated to shift the rock-bar forwardly thus to raise the fulcrum point, and due to the existence of the arcuate slot 45 159, the lifting of the presser-bar 56 is delayed until the fulcrum is out of engagement with the lever 77.

Upon releasing the manually applied force exerted on the treadle chain 106, the above described mechanism will return to its normal position (shown in Fig. 10) under the force of a pair of tension springs 165 and 166 which are effective to retension the coil spring 78. At their upper ends, both springs 165 and 166 are secured to the 55 frame 103 by means of a screw 167, and at their lower ends they are secured to the upper portion of a flexible steel band 168 which is fixed, by means of a screw 169, to an eccentric hub 170 carried upon an end of the shaft 115. As stub-shaft 60 115 also carries the gear 114, it will be understood that as the eccentric hub 170 is rotated in a clockwise direction it will place the springs 165 and 166 under increased tension so that they will urge the shaft 115 to rotate in an opposite direction 65 when the force is removed from the chain 106. These springs are of sufficient strength to drive the entire mechanism back to its initial position as they act through the toggle links 129 and 130 which are designed to have sufficient mechanical 70 advantage to overcome the force of the springs 78. It is to be noted that the hub 170 is shaped in a manner such that the initial movement thereof, in a clockwise direction from the position shown in Fig. 10, will impart to the springs 75 165 and 166 the major portion of the increased

11

tension, and that the further movement of the hub will impart a lesser degree of tension to the springs. By means of this hub construction, no undue tension will be imparted to the springs.

The presser-bar and top feed-bar may be locked in their respective raised positions by means of a vertically disposed lock-pin mounted in a lug 171 provided on the machine head 19. This lock-pin device comprises a hollow stationary sleeve 172 fitted into the lug 171 and secured therein by means of a set screw 173. Slidably mounted within the sleeve 172 is a cylindrical pin 174 having a slab-sided upper portion 175 which enters a corresponding slot 176 provided within the upper portion of the sleeve 172. This pin 174 is adapted to be raised manually against the force of a small coil spring 177 and then turned so that the slab-sided portion 175 of the pin is out of phase relative to the slot 176, which latter action is effective to lock the pin in its raised position as shown in Fig. 5. As the pin is located beneath the top feed-lift lever 52 it is effective, in its raised position, to prevent the lever and consequently the presser-bar and top feed-bar from returning to their normal lowered position.

The present device, therefore, provides a means whereby the presser-bar and/or the top feeding mechanism of a sewing machine may readily be raised above the work with the expenditure of a minimum amount of energy by the operator.

Furthermore, this device enables the presser-mechanism to be equipped with a spring of requisite strength, as the device provides for easily relaxing any spring that may, with advantage, be applied to a sewing machine presser-mechanism.

Having thus set forth the nature of the invention, what I claim herein is:

1. A presser-mechanism for sewing machines having a frame including a work-support, comprising, a presser-bar, a lever having one end portion thereof in operative engagement with said presser-bar, fulcrum means in engagement with an intermediate portion of said lever, a spring in engagement with the other end portion of said lever and being effective to bias said presser-bar toward said work-support, means to remove the force of said spring from said presser-bar, and means operable upon the removal of said spring force from said presser-bar for shifting said presser-bar away from said work-support.

2. A presser-mechanism for sewing machines having a frame including a work-support, comprising, a presser-bar, a lever having one end portion thereof in operative engagement with said presser-bar, fulcrum means in engagement with an intermediate portion of said lever, a spring in engagement with the other end portion of said lever and being effective to bias said presser-bar toward said work-support, and manually operable means upon an initial movement of which the force of said spring is removed from said presser-bar and upon a further movement of which the presser-bar is shifted away from said work-support.

3. A presser-mechanism for sewing machines having a frame including a work-support, comprising, a presser-bar, a lever having one end portion thereof in operative engagement with said presser-bar, fulcrum means in engagement with an intermediate portion of the lever, a spring in engagement with the other end portion of said lever and being effective to bias said press-

12

er-bar toward said work-support, means for removing the force of said spring from said presser-bar preparatory to shifting said presser-bar, means for moving said fulcrum means out of engagement with said lever, and means for shifting said presser-bar away from said work-support.

4. A presser-mechanism for sewing machines having a frame including a work-support, comprising, a presser-bar, a lever having one end portion thereof in operative engagement with said presser-bar, a fulcrum in engagement with an intermediate portion of said lever, a spring in engagement with the other end portion of said lever and being effective to bias said presser-bar toward said work-support, means for removing the force of said spring from said presser-bar preparatory to shifting said presser-bar, and means actuated by said first mentioned means for shifting said presser-bar away from said work-support upon the removal of said spring force from said presser-bar.

5. A presser-mechanism for sewing machines having a frame including a work-support, comprising, a presser-bar, a lever having one end portion thereof in operative engagement with said presser-bar, a fulcrum in engagement with an intermediate portion of said lever, a spring in engagement with the other end portion of said lever and being effective to bias said presser-bar toward said work-support, means for moving said fulcrum out of engagement with said lever preparatory to shifting said presser-bar, and means actuated by said first mentioned means for shifting said presser-bar away from said work-support.

6. A presser-mechanism for sewing machines having a frame including a work-support, comprising, a presser-bar, a spring for pressing said presser-bar toward said work-support, a manual control member, means including a toggle mechanism connected with said member for removing the force of said spring from said presser-bar, presser-bar lifting means connected with said member and being effective to shift said presser-bar away from said work-support, and lost-motion mechanism associated with said member for forcing said toggle mechanism and said presser-bar lifting means to be operated successively by a single continuous movement of said member.

7. A presser-mechanism for sewing machines having a frame including a work-support, comprising, a presser-bar, a spring for pressing said presser-bar toward said work-support, a manual control member, spring-disengaging means connected with said member for removing the force of said spring from said presser-bar, presser-bar lifting means connected with said member and being effective to shift said presser-bar away from said work-support, and means including a Geneva stop mechanism associated with said member for timing the actions of said spring-disengaging means and said presser-bar lifting means so that they may be operated successively by a single continuous movement of said member.

8. A presser-mechanism for sewing machines having a frame including a work-support, comprising, a presser-bar, a spring for biasing said presser-bar toward said work-support, means interposed in operative relation between said spring and said presser-bar for multiplying the applied force of said spring and applying the resultant upon said presser-bar, a manual control member, spring-disengaging means connected with said member for removing the force of said spring

from said presser-bar, presser-bar lifting means connected with said member and being effective to shift said presser-bar away from said work-support, and means including a Geneva stop mechanism associated with said member for timing the actions of said spring-disengaging means and said presser-bar lifting means so that they may be operated successively by a single continuous movement of said member.

9. A presser-mechanism for sewing machines having a frame including a work-support, comprising, a presser-bar, a spring for urging said presser-bar toward said work-support, a manual control member, spring-disengaging means connected with said member for removing the force of said spring from said presser-bar, presser-bar lifting means connected with said member and being adapted to shift said presser-bar away from said work-support, a first Geneva stop mechanism interconnected between said member and said spring-disengaging means, a second Geneva stop mechanism interconnected between said member and said presser-bar lifting means, and means interconnected between said member and said first and second Geneva stops for timing the actions of said spring-disengaging means and said presser-bar lifting means so that they may be successively operated by a single continuous movement of said member.

10. A presser-mechanism for sewing machines having a frame including a work-support, a presser-bar, a spring for urging said presser-bar toward said work-support, means interposed in operative relation between said spring and said presser-bar for multiplying the applied force of said spring and applying the resultant upon said presser-bar, spring-disengaging means including a toggle mechanism effective to remove the force of said spring from said presser-bar, presser-bar lifting means effective to shift said presser-bar away from said work-support, a pair of Geneva stop mechanisms, one of said Geneva stop mechanisms being associated in driving relation with said spring-disengaging means, the other Geneva stop being associated in driving relation with said presser-bar lifting means, and a manual control means connected to said Geneva stop mechanisms so as successively to actuate said spring-disengaging means and said presser-bar lifting means by a single continuous movement of said manual control means.

11. A presser-mechanism for sewing machines having a frame including a work-support, comprising, a presser-bar, a lever having one end portion thereof in operative engagement with said presser-bar, spring means in engagement with the other end portion of said lever and being effective to bias said presser-bar toward said work-support, fulcrum means in engagement with an intermediate portion of said lever, a manual control element, spring-disengaging means connected with said control element for removing the force of said spring from said presser-bar, fulcrum shifting means connected with said control element for shifting said fulcrum away from said lever, presser-bar lifting means connected with said control element for shifting said presser-bar away from said work-support, and means associated with said control element for timing the actions of said last three mentioned means so that they will be successively operated by a single continuous movement of said control element.

12. In a sewing machine having a frame including a head and a work-support, the combi-

nation of a presser-bar slidably mounted within said head, a spring for pressing said presser-bar toward said work-support, means comprising a lever of the first order interposed between said spring and presser-bar for imposing upon said spring a range of movement materially longer than that of said presser-bar, force-multiplying means for removing the pressure of said spring from said presser-bar, and manually controlled means operable upon removal of said spring pressure from said presser-bar for shifting said presser-bar away from said work-support.

13. In a sewing machine, the combination of a plurality of work-engaging feet, a spring for pressing said feet upon the work, means interposed in operative relation between said spring and said feet for imposing upon said spring a range of movement materially longer than that of either of said feet, means for imparting mutually alternating lifting movements to said feet against the force of said spring, manually controlled means including a force-multiplying mechanism for removing the pressure of said spring from said feet, and means actuated by said manually controlled means and operable upon removal of said spring pressure from said feet for shifting said feet away from said work-support.

14. The combination in a sewing machine having a frame including a work-support, a reciprocating presser-foot carrying bar, a feeding-foot carrying bar mounted for endwise reciprocating and laterally jogging work-feeding movements, means for reciprocally actuating said bars in directions toward and from said work-support, a spring for biasing each of said bars toward said work-support, manually controlled means including a force-multiplying mechanism for removing the pressure of said spring from each of said bars, and means actuated by said manually controlled means and operable upon the removal of said spring pressure from said bars for shifting said bars away from said work-support.

15. In a sewing machine, the combination of a plurality of work-engaging feet, a swinging arm, a pivotal support for said arm, separate connections between said arm and said feet, a lever having one end thereof connected with said arm, a spring connected to the other end of said lever so as to force said feet against the work, a fulcrum member cooperatively associated with said lever and in engagement therewith at a point adjacent the arm so as to provide the spring with a range of movement materially longer than that of either of said feet, means to shift said fulcrum member away from said lever, and means effective upon the removal of said fulcrum from said lever to shift said feet away from the work.

16. A presser-mechanism adapted to be used with a machine of the class described having a presser-bar and a spring for biasing said presser-bar toward said work, said presser-mechanism comprising, a manual control member, a first Geneva stop mechanism operatively connecting said manual control member with said spring and being effective upon an initial movement of said control member to remove the force of said spring from said presser-bar, a second Geneva stop mechanism connecting said manual control member with said presser-bar and being effective upon the removal of said spring force from said presser-bar to raise said presser-bar off the work, and means associated with said control lever for shifting said manual control member back into its initial position

upon the release of all manual control therefrom.

17. A presser-mechanism adapted to be used with a machine of the class described having a presser-bar and a spring for biasing said presser-bar toward said work, said presser-mechanism comprising, a manual control member, a first means operatively connecting said manual control member with said spring and being effective upon an initial movement of said control member to remove the force of said spring from said presser-bar, and a second means connecting said manual control member with said presser-bar and being effective upon the removal of said spring force from said presser-bar to raise said presser-bar off the work; said first and second means each comprising, a driving element, a driven element, a pin member carried by said driving element, and a complemental member carried by said driven element coacting with said pin and shaped to permit said pin member to impart a driving impulse to said driven member succeeded in one of said means and preceded in the other of said means by a dwell.

18. In a sewing machine, the combination of a presser-bar, a spring to bias said presser-bar toward the work, a manual control member, force-multiplying means connected with said control member and being effective to remove the force of said spring from said presser-bar upon an initial movement of said control member, presser-bar lifting means connected with said presser-bar and being effective to shift said presser-bar away from the work upon the removal of the spring force from said presser-bar, means associated with said control member for shifting the latter into its initial position upon the release of all manual control therefrom, and a pair of timing devices, one of said devices being positioned between said control member and said force-multiplying means, the other of said devices being positioned between said control member and said presser-bar lifting means, said pair of timing devices each comprising, a driving element, a driven element, a pin member carried by said driving element, and a complemental member carried by said driven element coacting with said pin and shaped to permit said pin member to impart a driving impulse to said driven member succeeded in one of said devices and preceded in the other of said devices by a dwell.

19. A presser-mechanism for sewing machines having a frame including a work-support, comprising, a presser-member, a lever disposed in operative engagement with said presser-member, fulcrum-means in engagement with said lever, an arm sustained by said frame, a spring interposed between said arm and said lever for biasing said presser-member toward said work-support, means for causing relative movement between said lever and arm to relax said spring preparatory to shifting said presser-member, means for moving said fulcrum-means out of engagement with said lever, and means for shifting said presser-member away from said work-support.

20. A presser-mechanism for sewing machines having a frame including a work-support, comprising, a presser-member, a relatively rigid lever disposed in operative engagement with said

presser-member, a shiftable fulcrum having an operative position in engagement with said lever and an inoperative position out of engagement with said lever, a spring connected to said lever for normally biasing said presser-member toward said work-support, means for shifting said fulcrum from its operative position to its inoperative position preparatory to raising said presser-member, and means for raising said presser-member from said work-support.

21. A presser-mechanism for sewing machines having a frame provided with a work-support, including, a presser-member, a lever disposed in operative engagement with said presser-member, a shiftable fulcrum having an operative position in engagement with said lever and an inoperative position out of engagement with said lever, a spring connected to said lever for normally biasing said presser-member toward said work-support, means for moving said fulcrum into and out of its operative position, and means rendered effective by the movement of said fulcrum for lowering and raising said presser-member relative to said work-support.

22. A presser-mechanism for sewing machines having a frame provided with a work-support, including, a presser-member, a lever disposed in operative engagement with said presser-member, a fulcrum-element turnable about an axis into and out of operative position with said lever, a spring connected to said lever for normally biasing said presser-member toward said work-support, manually controlled means for turning said fulcrum-element into and out of its operative position, and an arm operatively associated with said presser-member and connected to said fulcrum-element so that the turning of said fulcrum-element into and out of its operative position effects a lowering and raising of said presser-member relative to said work-support.

23. A presser-mechanism for sewing machines having a frame provided with a work-support, comprising, a presser-member, a lever disposed in operative engagement with said presser-member, a fulcrum-element turnable about an axis into and out of operative position with said lever, an arm sustained by said frame, a spring interposed between said arm and said lever for biasing said presser-member toward said work-support, first means for effecting relative movement between said lever and said arm to remove the force of said spring from said presser-member, second means operated automatically by and in series with said first means for turning said fulcrum-element out of its operative position, and third means rendered effective by the turning movement of said fulcrum-element for raising said presser-member from said work-support.
